UNITED STATES PATENT OFFICE.

JAMES H. BAKER, OF PITTSBURG, PENNSYLVANIA.

MACHINE FOR PUNCHING AND FORGING.

SPECIFICATION forming part of Letters Patent No. 671,431, dated April 9, 1901.

Application filed June 18, 1900. Serial No. 20,716. (No model.)

To all whom it may concern:

Be it known that I, JAMES H. BAKER, engineer, residing at Pittsburg, Pennsylvania, (post-office address Park Building, Pittsburg, 5 Pennsylvania,) have invented certain new and useful Improvements in Machines for Punching and Forging, of which the following is a specification, referring to the accompanying drawings.

10 The object of the invention is to improve and facilitate the punching and forging of metal, especially iron and steel, in a heated state. The machine works on the turret principle. The billet or blank to be worked upon 15 is in the preferred forms of the invention held by hydraulic grip or die, and the punching or forging tools are reciprocated to and from the billet or blank successively, one tool after another being brought into operation and being 20 mounted upon a turret, which reciprocates toward and from the billet. To facilitate explanation of the invention, I will describe one preferred embodiment of it. It is used for piercing or punching a hole through a billet, 25 although it must be understood that many other kinds of work can be done under the principles of my invention.

I will first point out some of the preferred forms and details of apparatus embodying 30 my invention, and I will then enumerate in the claims the novel and characteristic features.

In the drawings, Figure 1 is a plan view of the machine, with some features omitted for 35 clearness, showing the tool withdrawn from the billet-holding die. Fig. 2 is a partial view of the same, showing parts in section. Fig. 3 is a side elevation, partly in section and with some parts omitted. Fig. 4 is a similar view 40 of the machine after four successive reciprocations, showing the position at the forward end of the fourth stroke of the machine. Fig. 5 is a detailed view, partly in section, showing parts in position at the beginning of the 45 first stroke of the machine. Fig. 6 is a similar view showing the position at the forward end of the first stroke. Fig. 7 is a detail of certain other parts in the position corresponding to Fig. 6. Fig. 8 is a detailed plan view 50 of part of same. Fig. 9 is a detailed cross-section of certain parts. Figs. 10, 11, and 12

are detailed views, partly in section, of the centering and supporting mechanism for the punching or forging tool; and Fig. 13 is a detailed view of the billet-holding jaws, as seen 55 at right angles to Fig. 3.

Throughout the drawings like numerals of reference indicate like parts.

The frame of the machine 10 carries the stationary lower billet-holding jaw 11 and is 60 provided with slideways or guides 20 for the reciprocating tool-head 21. The main shaft 30, which is driven from any suitable source of power, has bearings in the frame or housing 10 and is connected by crank 22 and pit- 65 man 23 to operate the cross-head or slide 21.

Before going into details I will explain briefly that the cross-head 21 carries the turret-like adjustable tool-holder 40 which in the form shown in the drawings is provided 70 with four tools and is operated to turn on the horizontal shaft 41 in the cross-head 21. At each reciprocation one of the piercing or forging tools is forced into the billet and then withdrawn. Immediately after its withdrawal 75 the tool-holder 40 turns so as to present the next tool in line with the billet ready for the next stroke of the machine.

I will now explain the construction and also 80 the operation of the several parts more in detail. The heated billet 13 immediately after being placed in the lower die or jaw 11 is gripped and held by the upper jaw 14, which moves vertically and is controlled by the piston-rod 15 and the hydraulic cylinder 16. 85 This hydraulic gripping mechanism is controlled by the three-way valve 17, which supplies water under high pressure to the upper end of the cylinder 16 or allows it to discharge from the cylinder at will. Pipe 18, 90 connected with a pressure-tank or other source of pressure, supplies pressure beneath the piston; but such pressure is much less than the downward pressure controlled by the valve 17. When, therefore, the valve 17 admits 95 pressure above the piston, the jaw descends and grips the billet; but upon reversing the valve 17 the pressure beneath the piston raises the piston and releases the billet.

The reciprocation of the cross head or slide 100 21 is effected by the crank 22 and pitman 30, as before described, and is controlled by a

clutch 31, which is designed to connect and disconnect the shaft 30 with the source of power, which may be a pulley 32 and belt 33. The clutch 30 is controlled by the treadle or 5 foot-lever 35, fulcrumed at 36 and connected to control the clutch 30 by the link 37, and any desired form of shifting-lever 38, the details of which are not material to the invention. By depressing the lever 35 the clutch is thrown 10 in and the machine started; but the lever 35 is locked in its raised position by means of a shoulder 50 on a depending rod or link 51, which engages the lever at 39 and in addition to locking it serves the function of forcing it 15 downward, as will be explained below. The shoulder 50 is drawn toward the lever, as seen in Fig. 4, and the lever 35 released by depressing the treadle 52 of lever 53. This lever 53 is fulcrumed at 54 and acts through the bell- 20 crank 55 and rod 56 to draw the link 51 into the position shown in the dotted lines in Fig. 3. The levers 53 and 35 are automatically locked in their lowest position by the spring-dog 57, which engages the projection 58 on the 25 lever 53, as shown in Fig. 5. The depression of the lever 52 by the foot of the operator presses it down on the lever 35 and causes the latter lever to throw in the clutch and start the machine. Thereupon the machine makes 30 its first stroke, forcing the first or shortest tool 42 into the billet and then drawing it back. The shaft 41 carries a ratchet 46, having teeth at angles corresponding with the angular positions of the several tools 42, 43, 35 44, and 45. At each backward reciprocation of the cross head or slide 21 the successive teeth of the ratchet 46 strike the end of the pawl 47 and turn the shaft 41 one step, so as to bring the next tool into position to operate 40 upon the billet at the succeeding forward stroke of the machine. The pawl is held up to its work by the spring 48 until the last tool has been brought into operation, and it is then automatically released, the machine stopped, 45 and the first tool is brought into operative position by the following agency: The removable releasing lug or ear 60 is placed upon the revolving adjustable tool-holder 40 in position to engage and actuate a small lever 61 at the forward end of the stroke of the 50 machine. The lever 62 is fulcrumed in a position to be actuated by the lever 61. Preferably the end of the lever 61 projects through an eye in the end of the lever 62, so as to 55 make a loose articulate connection therewith. The lower end of the lever 62 carries a connecting-rod 63, one end of which is connected by a lost-motion connection, such as a pin and slot 64, to the spring-dog 57, and the other 60 end of which actuates a small bell-crank 65, which is connected to the link 51, and thereby to the pawl 47. When the lug or ear 60 strikes and pushes the end of lever 61 to the left, as seen in Figs. 4 and 7, three effects are 65 produced. The link or rod 63 is forced to the left, and thereby the dog 57 is disengaged

from the projection 58, releasing the levers 53 and 35. Secondly, the link 51 is allowed to engage with the lever 35 and forced downward by the bell-crank 65, so that the shoulder 50 strikes the lever 35 at the point 39 and forces that end downward, disengaging the clutch mechanism 30, 37, and 38. Thirdly, the pawl 47 is drawn downward by the link 66 and the bell-crank 65, so that it will not engage 70 the ratchet 46. When, therefore, the momentum of the machine carries the reciprocating head 21 to either end of the stroke and withdraws the tool from the billet, the machine 75 stops, and the tool-holder 40 may be turned by 80 gravity or by hand to any position desired, so as to bring tool 42 or any of the other tools desired into line with the billet previous to starting the machine again. Of course the pawl 47 has to be held down, or else it would spring 85 upward immediately. Therefore I provide a spring-catch 67, which retains the parts in position, as in Fig. 4. When, however, the tool-holder is returned to its original position, as in Fig. 3, the cam surface or lug 70 upon the ratchet 46 pushes back the spring-catch 67, 90 leaving the parts in their original initial position. It is necessary to center and support the piercing or forging tool toward this forward movement. This I accomplish by two 95 laterally-moving guides 80, (see Figs. 2 and 10,) which embrace and center the projecting portion 81 of the tool-holder 40, one of which is provided with each of the several tools 42, 43, 44, and 45. The guides 80 are forced together to embrace and center the tool-holder by means of the two pairs of toggles 82, which are actuated by the cam-rods 83 and the double-acting cams shown in detail in Figs. 11 and 12. One of these cams 84 acts upon a 105 stud 85 within the strap 86 to force its rod 83 toward the right and straighten the toggles 82, thereby holding the corresponding guide 80 firmly against the tool-holder, so as to guide and center the operation of the tool. The 110 cam 84 is designed, as shown, so as to hold the toggles in this position during about three-quarters of the revolution, releasing them only as the tool is withdrawn toward the rear end of the stroke. The opening movement 115 of the toggles is performed by either cams 87, which act upon the abutting surfaces 88 of the respective rods 83 to force the toggle into the position shown in Fig. 2 when the tool has nearly reached the rearward end of its stroke 120 and just before the pawl 47 engages a tooth of the ratchet 46.

The operation of the machine is as follows: After inserting the billet and closing the jaw 14 upon it the treadle 52 is depressed and the 125 shoulder 50 is thereby drawn clear of the shoulder 39 and the lever 35 is depressed, throwing in the clutch 30 and starting the machine. At the same time the spring-dog 57 locks the levers in their depressed position. Thereupon the tool 42 is forced into 130 the billet and then withdrawn. After its

withdrawal the centering-guides 80 withdraw sidewise and immediately thereafter the pawl 47 engages and turns the ratchet 46, bringing tool 43 into alinement. Next the guides 80 again come into play, centering the tool 43 as it is moved toward the billet by the reciprocation of the cross-head 21. After the tool 43 is withdrawn the tools 44 and 45 are successively brought into play in a similar manner; but as the last tool 45 reaches the end of its forward stroke levers 61 and 62 are actuated and dog 57 and pawl 47 are withdrawn from engagement, the shoulder 50 is depressed and strikes against shoulder 39, disengaging the clutch mechanism, and the machine is brought to rest as the last tool 45 is withdrawn from its operation. If the momentum of the machine is found too uncertain to be depended upon to bring the machine to rest in the desired position, weights or springs may be utilized, as will be well understood in the art, for it is preferable that the machine should always be brought to rest when the tool-holder is at the rear end of its stroke.

25 It will be noticed that the detachable lug or ear 60 may be placed upon the tool-holder in other positions than that shown, so as to stop the operation after one, two, three, or four strokes, thus enabling me to provide for 30 the operation of only one tool or for two, three, or four tools, as the forging of the particular work in hand may require. For this purpose I provide suitably-placed holes 69, Fig. 4, for bolting on the lug 60 in the correct 35 positions for the respective tools.

Having now set forth my invention in one of its preferred forms and explained the manner in which it may be used, I claim and desire to secure by Letters Patent the following 40 as the characteristic features of the invention:

1. In a machine for piercing or forging metal, the combination of means for holding the metal to be treated, a tool-holder carrying a plurality of tools and movably mounted to permit the bringing of the tools severally into operative position; mechanism for reciprocating the holder, and coöperating mechanism for adjusting the tool-holder to present 50 the tools successively in operative position, substantially as set forth.

2. In a machine for piercing or forging metal, the combination of means for holding the metal to be treated, a tool-holder carrying a plurality of tools and movably mounted to permit the bringing of the tools severally into operative position; mechanism for reciprocating the holder, and coöperating mechanism for adjusting the tool-holder to present 55 the tools successively in operative position, and coöperating mechanism for centering and locking the tool-holder, substantially as set forth.

3. In a machine for piercing or forging 60 metal, the combination of means for holding

the metal to be treated, a tool-holder carrying a plurality of tools and movably mounted to permit the bringing of the tools severally into operative position, mechanism for reciprocating the holder, and means for centering 70 and locking the tool-holder to insure the correct position of the tool, substantially as set forth.

4. In a machine for piercing or forging metal, the combination of means for holding 75 the metal to be treated, a tool-holder carrying a plurality of tools and movably mounted to permit the bringing of the tools severally into operative position; mechanism for reciprocating the holder in line with the metal to 80 be treated, and coöperatively-timed mechanism for centering the tool in its proper alinement, substantially as set forth.

5. In a machine for piercing or forging metal, the combination of mechanism for gripping and ungrinding the metal treated, a reciprocating head, means for adjustably supporting a plurality of tools, and coöperating mechanism for reciprocating the said head and adjusting the tools successively, sub- 90 substantially as set forth.

6. In a machine for piercing or forging metal, the combination of mechanism for gripping and ungrinding the metal treated, a reciprocating head, means for adjustably supporting a plurality of tools, and coöperating mechanism for reciprocating the said head, adjusting the tools, and centering or locking them when acting upon the metal, substantially as set forth. 100

7. In a machine for piercing or forging metal, the combination of a metal-holder for the metal to be treated, a tool-holder carrying a plurality of tools, and adjustably mounted to allow the bringing of the tools severally into operative position, and means for approaching and withdrawing the metal-holder and tool-holder relatively to each other, substantially as set forth.

8. In a machine for piercing or forging 110 metal, the combination of a metal-holder for the metal to be treated, a tool-holder carrying a plurality of tools, and adjustably mounted to allow the bringing of the tools severally into operative position, and means for approaching and withdrawing the metal-holder and tool-holder relatively to each other and adjusting the tool-holder to present the tools successively in operative position, substantially as set forth. 115

9. In combination in a machine for piercing or forging metal and with the frame thereof provided with guideways, a reciprocating head mounted thereon, an adjustable tool-holder mounted on the head, and a pawl-and-ratchet mechanism actuated by the movement of the head to adjust the tool-holder, substantially as set forth. 125

10. In combination in a machine for piercing or forging metal and with the frame there- 130

of provided with guideways, a reciprocating head mounted thereon, an adjustable tool-holder mounted on the head, and a pawl-and-ratchet mechanism actuated by the movement of the head to adjust the tool-holder, actuating connections for the head, and mechanism for locking and releasing the tool-holder during its reciprocation, said mechanism being timed to unlock it when the tool is with-

drawn from the metal, substantially as set forth.

Signed this 24th day of March, 1900, at Pittsburgh, Pennsylvania.

JAMES H. BAKER.
